UNITED STATES PATENT OFFICE.

SAMUEL N. McCLEAN, OF CLEVELAND, OHIO, ASSIGNOR, BY MESNE ASSIGNMENTS, TO THE AUTOMATIC ARMS COMPANY.

GAS-OPERATED MACHINE-GUN.

1,005,263.

Specification of Letters Patent. Patented Oct. 10, 1911.

Application filed February 11, 1904. Serial No. 193,063.

To all whom it may concern:

Be it known that I, SAMUEL N. McCLEAN, a resident of Cleveland, Ohio, have invented a new and useful Improvement in Gas-Operated Machine-Guns, which invention is fully set forth in the following specification.

My invention relates to improvements in breech-loading discharge actuated guns, and more particularly to gas-operated machine guns.

The object of the invention is to improve and simplify the construction, operation and manufacture of these guns, to produce a gun having a small number of operating parts, which can be easily cared for, assembled and disassembled without tools, in which the parts can be interchangeable and readily removed and inserted, and to attain certain advantages in connection with the breech-mechanism, and in the feeding, firing and ejecting actions of the gun, as more fully pointed out hereinafter.

The invention set forth in the accompanying drawings comprises a gas-operated machine-gun having a reciprocating and rotating breech-block engaged by a gas-driven piston to operate the breech mechanism, and provided with an air-cushion to check the terminal movement of the piston and to control the speed of firing. The piston-rod also engages and operates an oscillating cartridge feed to consecutively feed the cartridges, and cooperates with a sear and trigger to control the firing action of the gun. The frame of the gun is provided with a vertical magazine for retaining and consecutively feeding the cartridges, and this feed is provided with spring-pressed feed-fingers engaging with the cartridges to retain and control the consecutive feeding action of the cartridges.

Figure 1 is a side elevation of the gun, showing the rear part of the frame and cap in central section, and the forward part of the frame and associated parts also in central section; Figs. 1^a, 1^b are details of the magazine and clip; Fig. 2 is a side elevation of the breech-block and piston-rod showing the forward end of the breech-block in central section and the shell extractors in elevation; Fig. 3 is a plan view of the breech-block, looking up at its underside, showing the drive-rod in cross-section, and showing a broken central section at the rear

end of the breech-block; Fig. 4 is a central sectional view of the rear end of the breech-block and associated parts; Fig. 5 is a cross-sectional view of the handle part of the frame showing the firing dial and associated parts; Fig. 6 is a rear end elevation of the gun; and Fig. 6^a details of the cartridge feed-finger mounting; Fig. 7 is a rear elevation of the cartridge-feeding fingers; Fig. 8 is a cross-section of the cartridge-feeding device; Fig. 9 is a side elevation; and Fig. 10 a front end elevation of the breech-block and associated parts; Fig. 11 is a central longitudinal section of the breech-block and associated parts, on the line 11—11, Fig. 10, and showing the shell extractors in elevation; Fig. 12 is a diagrammatic view of the cam in the breech-block, showing in section the arm on the piston co-operating with said cam; Fig. 13 is a broken sectional detail of the breech-block, showing the shell-extractors and associated parts in elevation; Fig. 14 is a broken sectional detail of the breech-block, showing the cartridge-ejector in elevation; Fig. 15 is a longitudinal sectional view of the cartridge feeding devices, with parts thereof and the piston-rod in elevation; Fig. 16 is a side elevation of the plate carrying the cartridge-feed devices, which latter are shown in dotted lines; Fig. 17 is a central sectional view of the cylinder head and gas-controlling devices; and Fig. 18 is an end elevation of the same. Fig. 19 is a broken side elevation showing the manner of removably connecting the gas tube or chamber to the barrel; and Fig. 20 is a front elevation of Fig. 19.

In the drawings, 1 is the gun-frame and 2 is the barrel secured within the forward end of the gun-frame by screw-threads 3 engaging corresponding threads in the frame. The breech end of the barrel is cut out or chambered, as at 4, and the interior of this chamber is provided with interrupted screw-threads 5 for the engagement of corresponding screw-threads on the breech-block, as will be hereinafter described. The gun-frame is provided with a longitudinal cylindrical channel 6, extending from end to end thereof in line with the barrel, and a second longitudinal cylindrical channel 7 underneath and parallel with the channel 6. The forward end of the channel 7 is in alignment with and is connected to the tube 8 within which is located the spring 110

9 which serves to drive the gas-piston forward after it has been impelled rearward by the gases of discharge. Within the tube 8 there is placed a loose sleeve 10 which serves as an abutment for the spring 9 while a latch 11 is pivoted in a slot in the under side of the frame and has its forward nose thrown inward by a spring 12, as shown in Fig. 1, so as to prevent the sleeve from moving rearward under the influence of the spring 9, unless the latch 11 is withdrawn. The rear end of the frame is closed by a cap 13, preferably secured to the end of the frame by interrupted screw-threads 14, the form of the cap being such that when it is in position it closes the ends of both of the cylindrical channels 6 and 7. The cap 13 has formed therein a dash-pot 15 in alignment with the reciprocatory movement of the breech block, and this dash-pot serves as a buffer and a means of controlling the reciprocations of the breechblock, as will be hereinafter more fully described. This cap has also formed thereon flanges 16 which may be engaged by any suitable tool, as, for example, the shoulder bar, to operate the cap to unscrew it to release it from the frame. Between the cylindrical channels 6 and 7 is a slot 8^a extending from the rear of the frame to a point considerably in advance of the rear end of the barrel, this slot being for the purpose of permitting the arm on the piston rod, hereinafter referred to, to project up into the cylindrical channel 6 and engage the breech block for operating the same. The under side of the frame is suitably slotted for the purpose of permitting the play of the sear and trigger mechanism, and the frame is provided with a handle part 17 which is suitably slotted and reamed out to form a housing for the trigger and the disk which controls the loading and firing action of the weapon.

45 The breech block 18, best shown in Figs. 2, 3 and 4, 9, 10 and 11, is provided with interrupted screw-threads of the usual or any suitable construction, extending from the front thereof preferably to near the rear end of the block, where there is a portion 19 that is free from screw-threads for the purpose of affording a bearing and guiding surface for the block within its cylindrical guide-way 6. This block is chambered out 50 and has on its under side a slot 20, the forward portion 21 of which is parallel with the axis of the block and the rear portion of which is oblique thereto, whereby a cam surface or surfaces are provided to be engaged by the arm on the piston rod of the gun for operating the block. The particular construction of this lot is best shown in Figs. 3 and 12. On one side of the slot is provided an unbroken cam surface 22 which 55 is engaged by a corresponding cam surface

on the arm 23 of the piston rod in the act of opening the breech. The opposite part of the cam portion is provided with a cam surface 24 substantially parallel with the cam surface 22 and a cam surface 25, formed 70 at an angle to the cam 24. On the arm 23 of the piston rod there are formed cam surfaces 26 and 27 for engagement with the cam surfaces 24 and 25, as will be herein-after more fully described. The forward 75 end of the breech block is bored out, as at 28, for the passage of the firing pin and is mortised, as at 29, to afford seats for the extractors 30. These extractors are similar in construction and are provided with the usual hook or claw for engaging the flange of the cartridge, and at the rear end with an arm entering somewhat freely into the mortise 29. Located in a suitable seat formed in the body of the breech block, is 80 a spring-pressed pin 31 whose spring acts to force the pin against the extractor and keep the same normally rocked forward in position to engage the flange of the cartridge, the extractor rocking about a pin 32. 85 This pin 32 is seated in a hole formed partly in the extractor and partly in the body of the breech block. The extractor moreover is provided with a suitable flange or thumb-hold 33, and by grasping the extractor by 90 said thumb-hold (see Fig. 13) and forcing the same back against the spring-pressed pin 31, the extractor can be freed from the retaining pivot pin 32 and readily removed, the pin 31 being retained in its position by 95 reason of the fact that the forward coil of its spring is small enough to grip and frictionally retain its grip upon the pin, while the rearward coil of the spring is slightly larger than its seat in the block so as to 100 secure frictional contact of the spring with the seat.

The rearward chambered-out portion of the breech block has a longitudinal slot 34 cut through its wall, and within this slot is 110 mounted the ejector 35. This ejector is in the form of a bar having an angular lug 36 turned to engage a shoulder 37 formed in the slot 34, the ejector being normally held in position with the lug 36 engaging the shoulder 37 by means of the spring 38 bearing upon the rear end of the ejector. The ejector is also provided with a cam shoulder 39 and on its inner edge there are two lugs 40 which engage the inner surface of the 115 walls of the breech block, as shown in Fig. 14. In assembling the ejector the lugs 40 are placed in position to register with grooves 41, formed in the side of the slot 34, and after the lugs 40 have passed through the grooves 41 the ejector is advanced to the position shown in Figs. 9 and 14, and retained in its forward position by the action of the spring 38 which holds the lug 36 in 120 engagement with the shoulder 37.

Within the rear end of the breech block is mounted a sliding plate or cup 42 in a position to be struck by the arm 23 of the reciprocating piston rod in the act of opening the breech, and thereby forced rearward against the tension of a spring or springs. In Fig. 4 but one spring, 43, is shown, whereas in Fig. 11 two springs 43 and 44 are shown, 44 being the lighter spring and receiving and resisting the backward movement of the piston plate 42 before it comes in contact with the spring 43. For the purpose of affording an abutment for the springs, and also for the purpose of securing a piston packing to the rear end of the breech block, there is formed on the interior of the breech block an annular screw-threaded shoulder, which is here shown in the form of a ring 45 against which the spring 43 reacts. The shoulder formed by this ring 45 might be otherwise formed, but the construction wherein the ring 45 is employed greatly facilitates the rapid and cheap machining of the parts. The interior of the ring 45 is screw-threaded, as above mentioned, and the plug 46 is screw-threaded therein so as to confine between its mushroom-shaped head and the rear end of the breech block a packing 47 of fiber, or other suitable material, the diameter of which is such as to cause it to fit snugly in the buffer cylinder 15 formed in the cap 13 at the rear of the gun-frame. The plate 42 is provided with a central opening or perforation 42^a and the screw-plug 46 has a like central opening or perforation 46^a, so that a restricted air passage is formed through the rearward part of the breech block for the purpose hereinafter to be described. The piston plate 42 is prevented from moving too far forward under the action of the springs by an annular shoulder 48, Fig. 11, formed on the interior of the block. The block has also formed thereon a radial lug or rib 49 (Fig. 9) which travels in a suitable groove 49^a formed on the interior wall of the cylindrical chamber 6 of the gun-frame, thereby preventing the breech block from turning, except when it is in position within the breech of the barrel, thus timing and controlling the locking and unlocking action of the bolt.

The operation of the breech mechanism, including the opening and closing of the breech, the placing of the cartridges in the receiver or chamber 6 in front of the breech block, and the ejection of the empty shell, are all performed by a gas-driven piston 135, receiving its motive power from the gases of discharge taken from the barrel, preferably near the muzzle. A piston rod 51 integral or rigid with the piston extends rearward through the tube 8 and into the cylindrical chamber 7 where it has rigidly secured thereto the arm 23 shown in Figs. 2, 12 and

15. This piston rod 51 is surrounded by the coiled spring 9, and passes through the sleeve 10 (Fig. 1), and is provided with a bottom rib 52 which snugly fits in a cut-out channel 53 (see Figs. 5 and 6) in the bottom 70 of the chamber 7, thereby serving to steady and guide the reciprocating movements of the piston rod. This piston rod or drive rod has also formed thereon sear notches 54 and 55 for coöperation with the sear to control the loading and firing action of the weapon. The firing pin, if desired, might be a loose pin mounted in the breech block, but as here shown it is in the form of a pin 56 rigidly secured to the arm 23 in position to enter the bored-out firing pin opening 28 in the breech block. Preferably the pin 56 is removably attached to the arm 23. The piston rod is also provided at one side, and preferably its right-hand side, 85 with a cam, preferably in the form of a cam groove 57, extending forward and downward from its rear end for the purpose of operatively engaging the parts to effect the placing of the cartridges within 90 the receiver as will be hereinafter described.

The gas-driven piston is located in a gas chamber 59 at the forward end of the gun, which chamber is preferably supported upon the gun-barrel by means of any suitable 95 bracket. Communication is established between the bore of the gun and the gas chamber 59 by an opening or openings leading from the gun bore to said chamber, in which chamber provision is made for controlling 100 the gas pressure in the chamber. The means for effecting this control are shown in Figs. 17 and 18. The forward end of the gas chamber 59 is closed by a screw-plug 60 inserted therein, through which plug openings 105 or ports 61 are formed, and all of these openings or ports are controlled by a valve 62 held yieldingly to its seat by a spring 63 reacting between the valve and the head of a mushroom-shaped screw 64, secured in the 110 central portion of the screw-cap or plug 60, as will be clearly understood from an inspection of Fig. 17. Preferably the hub or central portion of the cap 60 projects outward slightly, so as to form a guide for the valve 62 and is, or may be, polygonal in form in order to more effectively perform its guiding functions, as is shown in dotted lines in Fig. 18, where 65 indicates the polygonal guide for the valve 62.

The tension of the spring 63 holding the valve 62 to its seat is determined by the screw 64. When the gun is fired and the gases enter chamber 59, if the pressure is above the desired amount, the gases entering port 61 raise the valves 62 against the tension of its spring and escape until the pressure in the chamber 59 is reduced to the desired point, when the valve promptly closes. This construction, not only effec- 125 130

tively controls the pressure of the gas in the chamber 59, but is one which is readily removed in order that the chamber may be inspected and cleaned.

5 The gun is provided with a substantially vertical magazine 66 placed to one side of the gun frame, preferably the right-hand side as shown in Fig. 6, the magazine being provided with grooves or guide-ways 67 as 10 shown in dotted lines in Fig. 6, for engagement with the flanges of the cartridge or cartridge clips as the case may be. Adjacent to the bottom of the magazine there is an opening formed in the side of the cylindrical 15 chamber or receiver 6, and a table 68, shown in dotted lines in Fig. 6, is formed in the bottom of the magazine 66 to receive the lowermost cartridge. The outer wall of the magazine at its lower part is composed of 20 the flanged plate 69 (see Figs. 6, 8, 15 and 16). This plate is held in position against the flanges in the wall of the magazine by springs 70 (Figs. 6 and 8) which react between the gun frame and socket bearings 25 71 (Fig. 15) in the plate to hold it pressed outward firmly against the retaining flanges 72, 73, of the magazine.

Referring now to Figs. 15 and 16, this plate 69 has formed on its interior three 30 pairs of brackets 74, 75 and 76, which are bored out in alignment to form the bearings for the rock shaft 78, which shaft has a key-way 79 (Fig. 8) extending along its length. Feed levers 80, 80, are mounted on the rock-shaft 78 between the respective pairs of bearing brackets 74 and 75, and an operating arm or lever 81 (Fig. 8) is mounted on the rock-shaft 78 between the brackets 76. The feed levers 80, 80, and the arm or lever 40 81 are all provided with a key-way, as 82, (Fig. 8) and a key 83 enters the key-way 79 on the shaft and the ways 82 in the arms 80 and lever 81, thereby effectively securing the said parts to the shaft and compelling them 45 to turn therewith and yet permitting the ready disassembly of all the parts by merely removing the key 83. The rock-shaft 78 is normally held in the positions shown in Figs. 6 and 8, *i. e.*, with the feed levers 50 80 in their outermost position, by the action of a coiled spring 84 (Fig. 15) one end of which is secured to a collar 85 attached to the rock-shaft 78 by a set-screw 86, the other end of the spring being secured to the 55 bracket plate 69 at 87, so that the shaft is rocked in one direction against the tension of the spring 84, and is by the spring returned to its normal position when freed from the action of the drive rod, as will be 60 hereinafter explained.

For the purpose of holding the bottom cartridge in the magazine in place upon the table 68, until such time as it is to be fed into the receiver, and furthermore, for the purpose of steadyng the feeding action so that

the cartridge will be accurately thrown to its position in the receiver by the feed levers 80, the cartridge feed fingers 88 are employed, which bear yieldingly upon the cartridge while it rests upon the table 68 and 70 maintain their yielding bearing upon the cartridge during the action of the cartridge-feed levers 80. These cartridge-feed fingers may be placed on either side of the magazine without materially departing from the 75 spirit of the invention, and as here shown are located upon the left-hand side thereof. They have both an oscillating and a reciprocating action which is secured by pivoting the fingers 88 to a shank 89 (Fig. 7), a spring 80 90 engaging the two parts so as to normally hold the feed finger 88 in the position shown in Fig. 7. This shank 89 enters a channel 91, removably mounted in the side walls of the magazine (see Figs. 6, 6^a) and is downwardly pressed by a spring 92, the normal position of the parts being as clearly shown in Fig. 6. When the cartridge-feed levers 80 advance from right to left to throw the cartridge into the gun, the cartridge-feed 90 fingers 88 bear upon the surface of the cartridge, as shown in Fig. 6, but swing upon their pivot pins and at the same time slightly rise so as to allow the cartridge to pass under the lower end of the feed finger. It will be 95 readily perceived that this operation holds the cartridge at all times, firmly but yieldingly against the table and the cartridge-feed levers 80, and prevents any overthrow or misplacement of the cartridge which 100 might cause jamming or other inaccuracies in the loading action.

The rocking action of the shaft 78 is secured by the engagement of the inner end of the lever 81 on said shaft with the cam 105 groove 57 upon the rear end of the piston rod, the lever entering the rear end of said groove when the breech block has been drawn sufficiently to the rear to permit the cartridge to enter between the forward end 110 of the breech block and the rear end of the barrel, when the further rearward movement of the piston rod serves to depress the rear end of the lever 81, thereby rocking the shaft and throwing the feed-levers 80 115 inward and carrying with them the cartridge, as will be readily understood from an inspection of Figs. 6 and 8. As soon as the end of the lever 81 has reached the point 93 in the slot 57 (see Fig. 2), the spring 84 120 on the rock-shaft acts to return the shaft to its normal position, the end of the lever 81 traveling in the part 94 of the groove in the drive-rod, as shown in Fig. 2.

For the purpose of drawing the piston-rod 125 rearward either to open the breech or disassemble the parts, a sliding bar 95 (Fig. 6) is mounted in a slide-way in the frame and has a handle 96 secured thereto, as well as a lug 97. The shank 98 of the handle 130

registers with a slot 99 in the slide-way when the handle is raised, at which time the lug 97 lies in front of a corresponding lug 100 secured to the piston rod 51, as is clearly shown in Fig. 6. By grasping the handle 96, raising it until the shank registers with slot 99 and drawing the same rearward, the piston-rod may be withdrawn to the rear for the purpose of opening the breech; or, if the 10 cap 13 has been removed from the gun-frame, it may be withdrawn rearward so as to bring the breech-block out of the chamber 6, when it can be separated from the piston rod. Before it is possible, however, 15 to thus withdraw the piston rod so far to the rear, it is necessary to operate the catch 11 so as to free the sleeve 10 which forms the abutment for the spring 9. This being done all of the parts, piston-rod, sleeve, 20 spring and piston, as well as the breech-block, can be entirely withdrawn. It will be readily appreciated that the only tool necessary for thus disassembling the parts will be such a tool as would fit in between 25 the flanges 16 upon the cap 13, to give it a partial turn in order to disengage the interrupted screw-threads thereon, and as has been hereinbefore stated, the shank of the shoulder bar would form an effective tool 30 for this purpose. Moreover, for disassembling the parts connected with the feeding of the cartridges into the receiver, it will only be necessary to push in the lower part of the bracket plate 69 against the tension 35 of the springs 70, thereby freeing the flanges on the plate from the upper flanges 72 upon the magazine wall, when the entire bracket plate can be withdrawn from the gun. A very efficient means for thus pushing the 40 bracket plate in is secured by forming flanges 101 (Figs. 1, 6 and 8) upon the bracket plate, which flanges are adapted to receive the shank of the shoulder bar which may then be utilized for pushing the lower part 45 of the bracket plate inward as above suggested. The bracket plate having been removed from the magazine, it is only necessary to push out the key 83, when all of the parts, including the feed lever 80, operating 50 lever 81, and the rock shaft 78, can be removed.

From the foregoing, it will be appreciated that the entire disassembling of the gun can be readily accomplished without the use 55 of any special tools, and can be as readily and quickly assembled without tools.

Referring now to the sear and trigger devices, and the means for controlling the same, as shown in Figs. 1 and 5, the sear 102 is pivotally mounted in a lower extension of the frame, being preferably pivoted to a shank pin 103 which has bearing upon a spring 104, and the sear itself being normally held in an elevated position by a sear-spring 105. The sear itself is provided with

a sear-shoulder 106 for engagement with the sear-notches 54 and 55 upon the piston or drive-rod, and has at its rear end a notch 107. The trigger 108 is pivoted at 109, having an oblong pivot bearing 110, as shown by dotted lines in Fig. 1, and is normally held with its sear-engaging nose in elevated position by the trigger-spring 111. When the trigger is in its foremost position the trigger nose engages the upper surface of 70 the sear, and when in its rearmost position it engages the notch or shoulder 107 upon the rear end of the sear. The action of the trigger is controlled by a dial 112, housed in a recess in the handle part 17, as shown in 75 Figs. 1 and 5. This dial is secured to a pin 113, rigid with a handle 114, and a spring 115 reacts between the dial and a face-plate 116, closing the recess forming the housing for the dial. The handle 114 has formed thereon a lug 117 (Fig. 5) for yieldingly engaging recesses or notches 118, 119 and 120, all of which are clearly shown in Fig. 1, and another similar notch which does not appear in Fig. 1, since it is 80 covered by the handle 114. The dial plate is provided with shoulders 121, 122, 123 and 124, which shoulders act to limit the movement of the trigger by reason of the engagement of a lug 125 on the trigger and which 85 plays in a slot 126 (Fig. 5) so as to come in contact with the firing dial as the trigger is pulled.

By turning the dial to the position shown in Fig. 1, the shoulder 123 on the dial is 90 brought into position so as to allow the trigger to be pulled far enough to entirely depress the sear below both of the sear notches on the piston-rod 51, and the weapon automatically loads and fires as long as cartridges are fed thereto from the magazine, the operator merely holding the trigger with the lug 125 firmly against the shoulder 123. By adjustment to the other positions indicated by the notches 118, 119 and 120, the 95 trigger may be either locked so that it cannot be fired at all, or adjusted so that the sear will engage at each discharge with the sear notch 54 to hold the breech open for single loading or with the sear notch 55 for 100 magazine loading but single firing, the form of the various shoulders being such as to either permit the trigger when pulled to retain the sear entirely out of the line of both notches, as when it engages the upper surface of the sear, or to permit it to first engage the upper surface, withdraw the sear from engagement with the sear notch 54, and then slip off into engagement with the notch 107 which will permit the sear to rise into engagement with the notch 55, when a further pull will discharge the gun.

Referring to Figs. 19 and 20, the gas tube 8, the rear portion of which is shown in Fig. 1 attached to the gun frame, is supported at 105

its forward end upon the muzzle of the barrel by bracket lugs 130 oppositely disposed so as to afford a groove between them within which the flanges 131 of the gas chamber or 5 cylinder portion of the gas tube is slid from the rear until it abuts against a lug 132 which limits the forward movement of the tube or chamber. This portion of the tube constitutes a cylinder 59 which, as before 10 stated, is in direct communication with the bore of the barrel through suitable channels or passages shown in dotted lines at 134. Preferably there is a plurality of such channels as shown, though manifestly a single 15 channel of suitable shape and size might be employed, if desired. In Figs. 19 and 20 the end closure or cap of the gas tube, as shown in Fig. 17, is removed. This construction provides for the ready assemblage and dis- 20 assemblage of the tube at the muzzle end of the barrel.

The operation of the gun will be readily understood. The gases entering the gas chamber 59 through the openings 134, drive 25 the piston 135 rearward and with it the drive rod or operating slide 51. In its rearward movement the arm 23 on said slide first travels in the portion 20 of the actuating slot in the breech block and then impinges 30 upon the cam 22 which turns the breech block so as to unlock it, and on its further rearward movement the arm 23 strikes the spring-pressed plate or cap 42 covering the perforations 42^a therethrough. The spring 35 44 takes up the first part of the blow of the slide and is subsequently reinforced by the spring 43. The breech block is then driven rearward and just before it reaches its full open position, the piston on the end of the 40 breech block enters the dash-pot 15 in the cap of the chamber 6 and thus serves to relieve the shock and slow down the action of the breech block by reason of the air confined in the dash-pot, the air very slowly 45 escaping either past the piston or through the perforation 46^a, and the perforation 42^a in the spring plate. As soon as the breech block has come to rest, the springs 43 and 44 act to slowly advance the arm 23 of the 50 slide until the cam face 26 on said slide is brought into contact with the portion 25 of the double cam on the right-hand side of the slot, in which position, assuming the firing disk 112 to be set for single load and 55 firing, the notch 54 on the drive-rod is engaged by the sear and the parts are held in this position. A pull upon the trigger releases the sear from the notch 54 and permits the advance of the slide, and with it the arm 60 23, under the influence of the spring 9. During the rearward travel of the breech block, the lug 49 engages and travels in the groove 49^a, Fig. 1, so as to prevent the rotation of the breech block during its rearward travel, and 65 when the drive-rod is released from the sear

the engagement of the cam 25 with the cam 26 forces the breech block forward until the lug 49 is released from the groove 49^a which only occurs when the breech block has entered the breech chamber of the barrel in position to be turned to cause its interrupted threads to turn and lock with the corresponding threads in the breech of the barrel. The advance of the arm 23 at the instant the sear engages the notch 54 relieves the pressure of said arm on the spring plate 42, and uncovers the port 42^a therein so that air is enabled to enter through said restricted port and the restricted port 46^a into the dash-pot, the spring plate 42 being slightly advanced in front of 70 the spring 43 by the lighter spring 44. When the slide is relieved from the restraining action of the sear, the arm 23 advances, acting upon the cam 26 and the breech block 75 is prevented from turning by the engagement of the lug 49 on the breech block with a groove 49^a in the chamber 6. The block having been fully entered in the breech of the barrel, the action of the cam 26 on the cam face 25, commences the turning action 80 of the block to lock it and the cam 27 on the arm 23 then engages the cam 24 and completes the locking action. Owing to the difference in pitch between the cams 24 and 25 the tendency of the breech-block to turn 85 while the lug 49 is in groove 49^a is less while cams 26 and 25 are engaged than while cams 27 and 24 are acting. The sudden bringing forward of the breech block and the slide 90 under the influence of the spring 9, when the slide is released from the engagement of the sear, is slowed down and shock prevented by the engagement of the piston on the rear of the block with the dash-pot, the restricted 95 passages 42^a and 46^a permitting air to enter, which prevents too great a suction, but being in small enough quantity to cause a slight retardation of the closing action. In the act of opening the breech, the shoulder 100 39 upon the ejector impinges upon the corresponding shoulder 39^a (Fig. 6) in the receiver and suddenly throws the ejector inward, thereby forcing the cartridge out through the opening 39^b in the receiver, indicated by the dotted lines at the upper left-hand part of Fig. 6, this opening 39^b being the usual and well-known form of cartridge 105 ejector opening. In the opening movement of the reciprocating slide, 51, just after the breech block has been opened the full length 110 of a cartridge, the arm 81 (Fig. 8) of the cartridge feeding device enters the cam groove 57 at the rear end of the slide, thereby depressing the arm and advancing the feed levers 80 toward the receiver, carrying 115 with it the cartridge resting upon the table 68, the movement of the cartridge, however, being steadied by the action of the cartridge feed levers 88, as previously described. The 120 action of the cartridge is, furthermore, 125 130

steadied and its seat upon the cartridge feed levers 80 is rendered more firm and secure by reason of brackets 80* projecting laterally from the side of the feed levers, as shown 5 in full lines in Fig. 8 and in dotted lines in Fig. 6, said brackets having an upper surface curved to conform to the outline of the cartridge. The tension of the gases in the gas cylinder 59 and the violence with which 10 they impel the piston and its attached slide rearward, is determined by the adjustment of the screw 64 bearing upon the spring 63, which controls the valve 62 over the ports 61 at the forward end of the gas chamber.

15 It will be observed that the entire structure of the gun is very simple in character, and one readily assembled and disassembled without the employment of tools. By depressing the spring-catch 11 and removing 20 the cap 13, the piston and slide, the spring 9 and the breech block can all be readily and entirely withdrawn from the gun. It has heretofore been explained how, by simply pressing in the bracket plate 69 carrying the 25 cartridge feed devices, it can be readily removed from the gun, carrying with it all of the elements which operate to feed the cartridges, and by the removal of the key which connects the plate, the rock-shaft and the 30 levers thereon, the same may be all entirely separated. It will be understood that this key might, if desired, be integral with the shaft engaging grooves in the levers, or the levers mounted on the shaft might have keys 35 formed for engagement with a longitudinal groove in the shaft. Moreover, it will be understood that the tension of the spring 84 on said shaft, can be adjusted by merely loosening the set-screw 86 and turning the 40 collar 85 around the shaft in either direction, suitable depressions, if desired, being formed in the shaft to afford a secure hold on the set-screw.

45 Referring to the extractors, it has already been explained how, by reason of their construction and method of mounting, they can be readily disassembled by simply pushing them slightly back against the pins 31, and thereby freeing them from the pivot pins 32, 50 after which they can be lifted out of the extractor seats. The ejector may also be withdrawn from its seat by simply pressing it rearward against the tension of the spring 38 until the lugs 40 on the ejector register 55 with the grooves 41 in the side faces of the slot 34, when the ejector can be elevated out of the slot 34. The piston and buffer spring mechanism at the rear end of the breech block can be entirely disassembled by unscrewing the screw-plug 46 and the ring 45, when all of these parts can be readily removed. Usually the cartridges to be inserted 60 in the magazine are contained in a cartridge clip 140 (Fig. 1^b) of any desired or suitable construction and for the purpose of retain-

ing the cartridges in the clip until the latter is inserted into the magazine, said clip is provided with a spring-pressed retaining catch 141. This retaining catch is provided with a lug, or preferably a pair of lugs 142, 70 while the magazine has a cam surface 143 near its lower rear end so formed and positioned as to engage the cam lugs 142 on the catch 141 and withdraw said catch from underneath the cartridges as the clip is forced 75 into the magazine. The bottom portion of this cam surface is in the form of a rounded undercut lip 144 which acts to engage the lugs 142 and thereby hold the clip in the magazine, the spring of the catch 141 yielding 80 sufficiently to free the clip when force is applied to withdraw it from the magazine.

What is claimed is:

1. In a gun, the combination of a breech-block, a piston thereon having an air port 85 extending therethrough, a chamber within which the said block reciprocates, and a dash-pot in said chamber in position to be entered by said piston on its terminal rearward movement. 90

2. In a gun, the combination of a breech block, a piston thereon having an air port extending therethrough, a chamber within which the breech block reciprocates, a cap closing the rear end of said chamber and 95 having a dash-pot therein in position to be entered by said piston on its terminal rearward movement.

3. In a gun, the combination of a breech block, a piston thereon having an air port 100 extending therethrough, a chamber within which the breech block reciprocates, a slide imparting reciprocating movements to the block and controlling the passage of air through said port, and a dash-pot in said 105 chamber in position to be entered by said piston on its terminal rearward movement.

4. In a gun, the combination of a breech block, a piston thereon having an air port 110 extending therethrough, a chamber within which the breech block reciprocates, a discharge-actuated slide imparting reciprocating movements to the block and controlling the passage of air through said port, and a dash-pot in said chamber in position to be 115 entered by said piston on its terminal rearward movement.

5. In a gun, the combination of a breech block, a piston thereon having an air port 120 extending therethrough, a chamber within which the breech block reciprocates, a slide actuated by the gases of discharge imparting reciprocating movements to the block and controlling the passage of air through said port, and a dash-pot in said chamber in position to be entered by said piston on its 125 terminal rearward movement.

6. In a gun, the combination of a reciprocating breech block, a breech-block-operating slide, and a pair of buffer springs interposed 130

between the block and slide, first one and then both of said springs acting to cushion the blow of the slide upon the block.

7. In a gun, the combination of a reciprocating breech-block, a discharge-actuated breech-block-operating slide, and a pair of buffer springs interposed between the block and slide, first one and then both of said springs acting to cushion the blow of the 10 slide upon the block.

8. In a gun, the combination of a reciprocating breech block, a ported piston on the rear end thereof, a buffer spring carried by said block, a ported piston plate or cap over 15 said spring, a chamber within which the breech-block reciprocates, a dash-pot in said chamber in position to be entered by the piston on the rear end of the block, and a breech-block-operating slide engaging the 20 said piston plate or cap and controlling the port therein.

9. In a gun, the combination of a receiver chamber, a dash-pot in connection therewith, a breech-block forming a piston for engagement 25 with said dash-pot, an air-port leading from said dash-pot, and a breech-block-operating element controlling said port.

10. In a gun, the combination of a receiver chamber, a dash-pot therein, a breech-block 30 forming a piston for engagement with said dash-pot, a spring-pressed plate in front of the piston and having a port for the passage of air into and out of said dash-pot, and a breech-block-operating element controlling 35 said port.

11. In a gun, a receiver-chamber and a dash-pot in line therewith, a breech-block forming a piston movable in said chamber and dash-pot, a spring-controlled plate carried by said breech-block, a port or opening 40 through said piston and plate and breech-block-operating means opening and closing said port.

12. In a gun, a breech-block having an 45 ejector seat in the form of a slot through the walls of the block, an ejector seated in said slot and having lugs engaging the interior surface of the block, and grooves formed in one wall of the slot and arranged 50 to register with said lugs when the ejector is slightly shifted from normal position, whereby the ejector may be readily placed in position and removed therefrom.

13. In a gun, a breech-block having an 55 ejector seat in the form of a slot through the wall of the block with grooves extending across one face of the slot, an ejector mounted in said slot and having lugs spaced to register with said grooves when the ejector 60 is slightly to the rear of its normal position, a bearing point on the breech-block around which the ejector normally turns, and a spring holding the ejector against said point.

14. In a gun, a breech-block having a cartridge-ejector seat in the form of a slot 65 through the walls of the block, said slot having a groove in one of its faces, and an exterior recess at one side of the groove, and an ejector seated in said slot and having a lug fitting in said recess so as to have longitudinal play therein and also having a side lug registering with said groove when the ejector is in its rearward position.

15. In a gun, a breech-block having a cartridge-ejector seat in the form of a slot 75 through the walls of the block, said slot having a groove in one of its faces and an exterior recess at one side of the groove, an ejector seated in said slot and having a lug 80 fitting in said recess so as to have longitudinal play therein and also having a side lug registering with said groove when the ejector is in its rearward position, and a spring pushing the ejector forward. 85

16. In a gun, a receiver, a breech-block having an ejector seat with one or more lateral grooves, an ejector having a lug or lugs registering with said grooves only when the ejector is shifted from its normal position, a cam on the ejector, and a shoulder in the receiver for operating the ejector. 90

17. In a gun, a breech-block having an interior chamber, a longitudinal slot through the walls of the block into said chamber and 95 having a groove formed in one of its faces and a recess on the side of said slot of greater width than said groove, an ejector having two lugs one of which has longitudinal movement in said recess and the other 100 of which normally engages the inner wall of the block, but registers with said groove when the other lug is at the rear of its recess.

18. In a gun, a chambered breech-block 105 having a slot in its wall, and an ejector seated in said slot and having a lug at one end engaging the exterior of the block and having another lug engaging the interior of the block. 110

19. In a gun, a chambered breech-block having a slot in its wall, an ejector seated in said slot and having a lug at its rear end engaging a shoulder on the outer part of the block and another lug engaging the interior 115 wall of the block, and a spring holding the first-mentioned lug yieldingly against said shoulder.

20. In a gun, a receiver, a reciprocating and rotating chambered breech-block having 120 a longitudinal slot in its wall, an ejector seated in said slot and having a lug at one end engaging the exterior of the block and another lug engaging the interior of the block, a cam on the ejector and a shoulder 125 on the receiver in the path of the cam on the ejector, and a gas-driven piston operatively engaging the breech-block.

21. In a gun, a reciprocating and rotating breech-block, a piston on the rear end of the block, a buffer or cushion carried by the block, a receiver having a dash-pot in line 65 with the breech-block, and a gas-driven slide operatively engaging said block and also engaging said buffer or cushion.
22. In a gun, a gas cylinder communicating with the gun bore, a piston in said cylinder, a removable closure for the front end of 10 said cylinder, ports through said closure and an automatic relief valve controlling said ports.
23. In a gun, a gas cylinder communicating with the gun bore, a piston in said cylinder, a removable closure for the front end of 15 said cylinder, ports through said closure, a valve controlling said ports, a spring bearing on said valve and a screw regulating the tension of said spring.
24. In a gun, a barrel, a gas cylinder communicating with the gun bore, vent ports to the atmosphere, a piston in said cylinder, and a valve controlling said ports independent 20 of said piston.
25. In a gun, a gas cylinder, a piston therein, a port connecting the barrel with said gas cylinder on the working side of 25 said piston, a vent port or ports for said gas cylinder leading from the working side of the piston to the atmosphere, and a spring-pressed valve controlling said port or ports.
26. In a gun, a gas cylinder communicating with the gun bore, vent ports to said cylinder, a spring-pressed valve controlling 30 said ports, and a screw adjusting the tension of said spring.
27. In a gun, the combination of a breech block, a gas-driven slide operatively engaging 35 said block, chambers in which said block and slide reciprocate, a collar surrounding said slide within one of said chambers, a catch restraining said collar against rearward movement, and a spring reacting 40 between said collar and a piston on the slide.
28. In a gun, a breech-block, a gas-driven piston operatively connected thereto, a chamber within which said piston works, and automatic means limiting the gas pressure 45 within said chamber.
29. In a gun, a piston actuated by the gases of discharge, and automatic means limiting the gas pressure on the piston to a predetermined degree.
30. In a gun, a gas chamber communicating with the bore, a vent port or vent 50 ports to the atmosphere, a reciprocating piston in said chamber, and an automatic relief valve independent of said piston controlling said vent port or ports.
31. In a magazine gun, a cartridge-feed mechanism for inserting the cartridges into the receiver, a removable bracket plate upon 55 which said feed mechanism is mounted, and discharge-actuated means operatively connected to said feed mechanism.
32. In a magazine gun, a rock-shaft mounted in a removable bracket plate, cartridge-feed levers on said rock-shaft, a discharge-actuated slide and operative connections between said slide and rock-shaft.
33. In a magazine gun, transversely-operating cartridge-feed mechanism and a removable plate on the side of the magazine supporting said feed mechanism.
34. In a magazine gun, a bracket plate having flanged engagement with the walls of the magazine, cartridge-feed mechanism supported on said plate, and yielding devices holding said plate in engagement with the flanges on the magazine.
35. In a magazine gun, a removable bracket plate forming the lower wall of the magazine, and cartridge-feed mechanism removably secured to said bracket plate.
36. In a magazine gun, a bracket plate yieldingly held in flanged engagement with the magazine, bearing brackets on said plate, an operating lever and a cartridge-feed lever held between said bracket bearings, and a rock-shaft passing through said levers and brackets and keyed to said levers.
37. In a magazine gun, a removable bracket plate, bracket bearings on the interior of said plate, a cartridge-feed lever and an operating lever located between said bracket bearings, a rock-shaft passing through said bearings and said levers and a key securing said levers and rock-shaft together.
38. In a magazine gun, a removable bracket plate, a plurality of bearing brackets on the face of said plate, a cartridge-feed lever and operating lever located between said bracket bearings, a rock-shaft keyed to said levers and passing through said bearings, and a gas operated slide engaging said operating lever.
39. In a magazine gun, an oscillating and reciprocating cartridge-feed finger and means holding the same in yielding contact with the cartridge.
40. In a magazine gun, a cartridge-feed finger, a shank to which said finger is pivotally united, a guide-way within which said shank is located, and a spring pressing upon said shank, whereby the cartridge-feed finger is enabled to both oscillate and reciprocate under the feeding action of the cartridge.
41. In a magazine gun, a spring-pressed reciprocating and oscillating cartridge-feed finger removably mounted in the magazine.
42. In a gas-actuated automatic gun, the combination of a breech block, a gas-driven piston operatively engaging the same, a spring for moving the piston forward and an adjustable abutment for the rear end of

said spring whereby it may be put under tension or the tension thereof be released at will.

43. In a gas-actuated automatic gun, the combination of a reciprocating piston rod and a breech block operatively connected thereto, with a spring for impelling the piston rod forward, a sleeve surrounding the piston rod and forming an abutment for the rear of said spring, and means for adjusting

said sleeve upon the rod to place the spring under tension or relieve it from tension at will.

In testimony whereof I have signed this specification in the presence of two subscribing witnesses.

SAMUEL N. McCLEAN.
